US0D1100408S

(12) **United States Design Patent** (10) **Patent No.:** **US D1,100,408 S**
(45) **Date of Patent:** **** Oct. 28, 2025**

(54) **PALLET**

(71) Applicant: **The Hershey Company**, Hershey, PA (US)

5,791,262 A 8/1998 Knight et al.
D399,631 S 10/1998 Campbell
D428,679 S 7/2000 Bridge
6,101,955 A 8/2000 Salce
(Continued)

(72) Inventor: **Steven A. Weis**, Hershey, PA (US)

FOREIGN PATENT DOCUMENTS

(73) Assignee: **The Hershey Company**, Hershey, PA (US)

WO 87/05580 A1 9/1987
WO 94/10051 A1 5/1994
(Continued)

(**) Term: **15 Years**

(21) Appl. No.: **29/917,686**

(22) Filed: **Nov. 21, 2023**

FIG. 1 is a top perspective view of a pallet showing the design;

FIG. 2 is a top view thereof;

FIG. 3 is a first side view thereof;

FIG. 4 is a second side view thereof;

FIG. 5 is a first end view thereof;

FIG. 6 is a second end view thereof;

FIG. 7 is a bottom view thereof; and,

FIG. 8 is a bottom perspective view thereof.

The dot-dash broken lines indicate the boundaries of the claim that form no part of the claimed design. The evenly spaced broken lines depict environment that form no part of the claimed design.

1 Claim, 5 Drawing Sheets
